UNITED STATES PATENT OFFICE.

CHRISTOPH METTLER, SR., OF MENNO, SOUTH DAKOTA.

GRAIN ELEVATOR.

Application filed July 9, 1920. Serial No. 395,051.

To all whom it may concern:

Be it known that I, CHRISTOPH METTLER, Sr., a citizen of the United States, and a resident of Menno, in the county of Hutchinson and State of South Dakota, have invented certain new and useful Improvements in Grain Elevators, of which the following is a specification.

This invention relates to improvements in grain elevators.

The object of the invention is to provide an improved grain elevator in which excessive pressures and undesirable overflow resulting from clogging of the elevator system are automatically prevented, the excessive grain being received and carried off by means provided for that purpose.

Another object of the invention is to provide an improvement of this character of simple and durable construction, reliable in operation and easy and inexpensive of manufacture.

Other objects and advantages reside in certain novel features of the construction, arrangement and combination of parts which will be hereinafter more fully described and particularly pointed out in the appended claims, reference being had to the accompanying drawing, in which—

Figure 1 is a side elevational view of the improvement;

Figure 2 is a transverse vertical section of a portion thereof;

Figure 3 is an end elevation of the distributor head and its associated structure;

Figure 4 is a detail view in horizontal section, on the line 4—4 of Figure 1.

Referring to the drawings, it will be seen that the invention is embodied in a grain elevator which includes an elevator discharge head 10 having, as usual, an inclined bottom 10^a, which receives the grain from the buckets 12^a of an elevator 12. The elevator 12 picks up and raises the grain from the grain pit or similar structure (not shown).

A distributor head 13 receives the grain from the lower open end of the elevator discharge head. As shown in the drawings, the distributor head 13 is provided at its upper end with an outwardly extending flange 13^a which engages with a similar flange 10^b formed on the elevator discharge head. Suitable fastening means 9 extend through and secure the flanges 13^a and 10^b together to secure the elevator discharge head to the distributor head. The lower half of the dis-

tributor head is inclined or angularly formed with respect to the upper half so as to provide a deflecting surface 13^b for the grain and an offset 13^c for a purpose to be herein-after more fully described. The lower end of the distributor head is provided with an inturned marginal flange 13^d, as clearly shown in Figure 2. A discharge hopper 14 is provided at its upper end with an outwardly extending marginal flange 14^a which engages the flange 13^d of the distributor head and is secured thereto by securing means 15.

A swiveled delivery spout 16 is carried by the lower end of the hopper 14 and is adapted to be turned to deliver the grain to the desired bin, freight car or the like. For this purpose the lower end of the hopper 14 is provided with an annular collar 14^b having an arcuate circumferentially extending slot 14^c formed therein. The upper end of the swiveled delivery spout is rotatably fitted over the collar 14^b and is provided with a radially extending pin 16^a which operates in the slot 14^c of the collar, thereby preventing displacement of the spout from the collar while permitting relative rotary motion thereof. A turning post 17 facilitates the adjustment of the swiveled delivery spout.

The offset 13^c of the distributor head is provided with an opening 13^e in its outer wall. This opening being formed in the outer wall of the offset 13^c lies well out of the normal path of the grain. A swinging closure, such as a swinging door 13^f, is provided for the opening 13^e, being hinged as at 13^g to the offset of the distributor head. The lower end of the door 13^f is weighted, as at 13^b, so that the door is normally maintained closed. A return chute 18 for the grain has its upper open end 18^a disposed directly beneath the vent opening 13^e to receive the flow from the opening. The return chute 18 is provided with a laterally extending lug 18^b secured as at 18^c to the flange 14^a of the hopper 14. The return chute 18 delivers the grain which flows therethrough from the opening back to the grain pit or the like from which the grain was originally raised by the elevator.

In practice, it will be seen that normally the grain is raised by the elevator 12 and delivered from the buckets 12^a thereof to the inclined bottom 10^a of the elevator discharge head 10. The grain flows along the

bottom 10^a to the distributor head 13 in which it strikes the surface 13^b and is deflected into the hopper 14 and thence through the swiveled delivery spout 16 to the desired grain bin, freight car or the like. During this operation the vent opening and its door are latent as they are well out of the path of the grain and in no way concern its normal flow. Should, however, the delivery spout, 10 hopper of the like become clogged or otherwise resist the flow of the grain there through the grain would tend to pile up and rise in the system and eventually overflow through the elevator discharge head, 15 mixing and scattering the grain. Moreover, if it were not relieved, the pressure thus created in the system would be so serious as to frequently result in injury or rupture of some of the elements of the system. 20 These undesirable conditions obtained in the art heretofore, but in this invention, as soon as the grain piles up into the elevator discharge head it, of course, spreads laterally and its weight and pressure swing the 25 closure 13^c outwardly so that the grain flows through the opening into the return chute 18 and through the return chute back to the grain pit. This return flow of the grain is equal to the feed thereof by the elevator 30 12 so that the grain cannot rise higher than the opening. This entirely relieves the excessive pressure which would otherwise exist and it also prevents the mixing up or scattering of the grain. It is entirely automatic in its operation and requires no attention, for as soon as the clogging is relieved the grain again flows in its normal path and does not exert any pressure or force upon the swinging closure 13^c which swings inwardly 35 40 to close the opening.

I claim:

1. In a grain elevator, a distributor head having a passage through which grain is

adapted to flow, said distributor head being provided with an offset portion having an 45 opening laterally spaced from the normal path of the grain through the distributor head, and means for normally closing said opening and operable by the pressure of the excessive grain accumulating in said distributor head to uncover said opening and permit discharge therethrough. 50

2. In a grain elevator, a distributor head having a passage through which grain is adapted to flow, said distributor head having an offset portion provided with an opening laterally spaced from the normal path of the grain, a swinging door having its lower end weighted for normally closing said opening and operable by the pressure of the 55 excessive grain accumulating within the distributor head to uncover said opening and permit discharge therethrough, and a chute arranged to receive the grain discharged from said opening. 60

3. In a grain elevator, an elevator discharge head, an elevator for raising the grain thereto, a swiveled delivery spout, a distributor head arranged between said elevator discharge head and said delivery spout 70 and having a passage extending from the distributor head to the delivery spout and through which the grain is adapted to flow, said distributor head being also provided with an offset portion having an opening 75 laterally spaced from the normal path of the grain through the distributor head, means for normally closing said opening and operable by the pressure of excessive grain within said distributor head to normally 80 open said opening and permit discharge therefrom, and a return chute arranged to receive the grain discharged from the opening and to deliver to the source of supply of the elevator. 85

CHRISTOPH METTLER, SR.
